DESIGN FOR AN INK BOTTLE

Gabriel Larsen, Springfield, N. J., assignor to
L. E. Waterman Company, New York, N. Y., a
corporation of New York

Application April 23, 1935, Serial No. 56,520

Term of patent 14 years

To all whom it may concern:

Be it known that I, Gabriel Larsen, a citizen of the United States, residing at Springfield, in the county of Union and State of New Jersey, have invented a new, original, and ornamental Design for an Ink Bottle, of which the following is a specification, reference being had to the accompanying drawing, forming a part thereof.

Fig. 1 is a vertical view of an ink bottle in one position;

Fig. 2 is a view similar to Fig. 1, but showing the bottle partly turned around a vertical axis from the position shown in Fig. 1;

Fig. 3 is a top plan view of the bottle.

I claim:

The ornamental design for an ink bottle substantially as shown.

GABRIEL LARSEN.
